UNITED STATES PATENT OFFICE.

JOHN C. CULLIGAN, OF BOMBAY, NEW YORK.

PACKAGE-TIE.

1,352,357.

Specification of Letters Patent.

Patented Sept. 7, 1920.

Application filed March 1, 1919. Serial No. 279,999.

To all whom it may concern:

Be it known that I, JOHN C. CULLIGAN, a citizen of the United States, residing at Bombay, in the county of Franklin and State 5 of New York, have invented new and useful Improvements in Package-Ties, of which the following is a specification.

This invention relates to a package tying device, and has for its object to produce a 10 simple means whereby a package may be tied in an easy, expeditious and efficient manner without necessitating the knotting of the tying cord.

A further object of the invention is to produce a package tie comprising a right angular member having a tying cord centrally secured thereon and the angle ends of the said member formed with jaws, each of which include a loop arranged over the said ends, 15 and each of said loops having their arms crossing each other at their connection to the angle ends of the body, so that when the cord engages between the jaws and the body the same will be twisted under one of the 20 strands and over the other strand of the jaw and thus effectively locked so that the tighter a pull exerted upon the cord the more tightly the same will be brought to engage between the jaw and body.

30 It is a further object of the invention to produce an extremely simple construction of tying devices which may be employed with equal efficiency upon flat or round packages without inflicting injury thereto, and which 35 may be cheaply manufactured and marketed.

Other objects and advantages will present themselves as the nature of the invention is better understood, reference being had to the accompanying drawings, in which:

40 Figure 1 is a view illustrating the improvement connecting a flat package.

Fig. 2 is a similar view showing the arrangement of the device upon a round package or roll.

45 Fig. 3 is a perspective view of the improvement.

The improvement is preferably constructed from a strand of spring wire bent upon itself to present a member which is right angular in plan, which construction permits of the same being arranged upon either a flat or a round package with equal efficiency and without danger of inflicting injury to the package.

The device thus comprises two right angular arms 4 and 5 respectively, the outer parallel strands of wire 6 of each of said arms, at the meeting ends thereof being rounded upon themselves to provide eyes 7 which interengage, and over one or both of these 55 eyes is secured the inner end of the tying cord 8. The inner strands 9 of the arms 4 and 5 are parallel to the outer strands 6, and at the bight or juncture between the inner and outer parallel strands the same are 60 looped upon themselves to provide jaws 10 that overlie the respective arms 4 and 5. The outer members or strands of each of the 65 spring jaws 10 lap each other at an angle to their connection with the strands 6 and 9 of the respective arms 4 and 5. By this arrangement it will be noted that when the 70 cord 8 is brought around either the flat package 11 or the round package 12 and engaged between the jaws and the angle arms 4 and 5 the said cord will be twisted between the 75 rounded end strands of the arms 4 and 5 and thelapping angular outer ends of the jaws so that an effective biting engagement will be maintained between the device and the 80 tying cord. The twisted cord engaged between the jaws and the arms is so gripped that a direct longitudinal pull thereon will only effect a tighter engagement between the 85 jaws and the arms, so that it is absolutely necessary to bring the cord longitudinally of the arms out of the jaws before the same can be removed from the device.

It is believed, from the foregoing description that the simplicity of the arrangement 90 and the efficiency thereof will be fully appreciated without further detailed description.

Having thus described the invention, what is claimed as new is:—

A package tie constructed from a strand 95 of wire and comprising a right angular body portion, comprising parallel inner and outer arms, said arms at their outer ends being rounded upon themselves and provided with connected extensions that overlie the said 100 arms and provide jaws, the outer arms providing the terminals of the wire strand and having their confronting face bent to provide interengaging eyes, and one of said eyes designed to receive a knotted tying cord 105 therethrough.

In testimony whereof I affix my signature.
JOHN C. CULLIGAN.
